(No Model.)

A. J. NORDMANN.
ALARM AND WAKING BED.

No. 325,437.

Patented Sept. 1, 1885.

FIG. 1.

FIG. 2.

ATTEST.

John H. Redstone
E. H. Sharp

INVENTOR.

Adolph J. Nordmann.

UNITED STATES PATENT OFFICE.

ADOLPH J. NORDMANN, OF SAN FRANCISCO, CALIFORNIA.

ALARM AND WAKING BED.

SPECIFICATION forming part of Letters Patent No. 325,437, dated September 1, 1885.

Application filed April 9, 1885. (No model.)

To all whom it may concern:

Be it known that I, ADOLPH J. NORDMANN, a citizen of the United States, residing in the city and county of San Francisco, 5 and State of California, have invented a new and useful Alarm and Waking Bed, of which the following is a specification.

My invention relates to improvements in "alarm and awakening bedsteads;" and it 10 consists in the construction and arrangement of a certain device for operating in connection with the alarm-clock for dropping the bed or a portion of the same at the time when the clock is set for alarming to awaken 15 the sleeper, and so derange the bed as to force him to rise.

The following is the construction of the same.

Figure 1 is an isometrical perspective view 20 of a bedstead with my improved alarm and awakener attached. Fig. 2 is an end elevation of the same, showing the head of the bed; and Fig. 3 is a front elevation of the alarm-clock with a part of the face broken 25 out to show the attachment of my improvement.

A represents the head-board; B, the foot-board; C, the posts; D, the side rails; E and F, the slat-frame; G, the joint at which the 30 slat-frame is hinged together.

H represents the bearing-springs.

I represents the clock-face.

J represents the alarm tripper and stop.

K represents the alarm cam and lever or 35 bed-dropper.

L represents the connecting-lever.

M represents the connecting-rod.

N represents the pawl.

O represents the ratchet-wheel.

P represents the winding drum or pulley.

Q represents the suspension-cord.

R represents the knob for attaching the suspension-cord to the head of the mattress-frame F, to hold the same up when in position as a bed.

S represents the winding-knob, T the winding-shaft.

The following is the operation of the same: The alarm attachment is that of any well-known alarm-clock, and I utilize the projection or bed-dropper K to trip the connecting-lever L, and at that point my invention begins. The alarm being wound and set for a certain hour, and the suspension-cord Q wound upon the drum P, thus holding the 55 mattress in a horizontal position, when the alarm is discharged the projection or tripper K passes on to the connecting or ratchet lever L, tripping the same and throwing it out of gear with the ratchet-wheel O, and consequently releasing the winding-drum B and lowering the mattress-frame F. Thus a person sleeping is awakened as the alarm sounds, and should he fail to rise he is immediately dropped down with the head portion of the 65 mattress F, which then has its bearing upon the springs H.

The mattress-frame E F may be constructed without a joint, G, or in one piece, in which case it is hinged at the foot, and the head is 70 dropped as in the case of the section F.

Having thus described my invention, what I claim, and desire to secure by Letters Patent, is—

1. In alarms and awakeners for bedsteads, 75 the connecting ratchet-lever L, in combination with the alarm-stops J, K, and V, for the purpose of releasing the ratchet-wheel O and dropping the mattress F, constructed and operated substantially as and for the purposes 80 set forth.

2. The suspension-cord Q, winding-drum P, shaft T, winding-knob S, and ratchet-wheel O, in combination with the ratchet lever or pawl N, the connecting-rod M, and the connecting-lever L, operated by the projection K, for the purpose of dropping the mattress F, constructed and operated substantially as and for the purposes set forth.

ADOLPH J. NORDMANN.
